UNITED STATES PATENT OFFICE.

GEORGE M. PETERSON, OF STURGEON BAY, WISCONSIN.

WORK-SUPPORTING STAND.

Application filed May 1, 1923. Serial No. 635,920.

This invention relates to motor stands such as are used in garages and machine shops for the purpose of supporting the motor block, transmission case, and other parts of a motor car when being overhauled.

The general object of the invention is to provide a motor stand of this character which is light and, therefore, readily shifted to any desired point of the machine shop, which is firm, and which may be disassembled for packing and shipment and may be readily assembled whenever desired.

A further object is to provide a motor stand of this character which will support the motor block, crank case and allied parts at the right height for overhauling and working thereon, and which is so constructed as to permit the motor block to be swung to a plurality of positions so as to make every part of the motor block readily accessible for operation.

A still further object is to provide in a device of this kind means for keeping the valves from dropping out when the motor block is swung to carry the cylinders into different angles, this means being so constructed as to enable the operator to turn the crank shaft and cam shaft without bending or buckling the valve stems.

Still a further object is to provide a construction of this character by which an entire motor can be assembled completely with crank case, transmission cover, etc.

Other objects will appear in the course of the following description.

My invention is illustrated in the accompanying drawings, wherein:—

Figure 1 is a perspective view of a work supporting stand constructed in accordance with my invention;

Figure 2 is a side elevation of the upper portion of the stand, showing two positions in which the motor may be adjusted;

Figure 3 is a sectional view through the bar 28, showing the means for engaging the engine block;

Figure 4 is a sectional view through the bar 28, showing the manner in which the pin 31 is mounted therein;

Figure 5 is a fragmentary sectional view through the engine block and the supporting bar 15 showing the manner in which the engine block is connected thereto.

Referring to these drawings, it will be seen that my stand comprises the horizontal

ly extending angle irons 10 which form the base of the device and to which are attached by bolts, rivets or other suitable means the upwardly extending standards 11, these standards being of relatively heavy iron or other like material. The standards extend upward and slightly inward, and disposed between the parallel portions of the standards is a block 12 of wood or other suitable material, this block being grooved upon its upper and lower faces, and passing through these grooves are the bolts 13 and 14 holding the block firmly in place, the block preventing any collapsing of the standards.

Mounted upon the upper ends of the standards for oscillation thereon is a transverse bar 15 having angularly bent ends 16 which extend down on the outside faces of the standards. Through this bar passes a bolt 17 carrying a nut 18 having a handle 19, and disposed between the standards and surrounding this bolt is a sleeve 20 which prevents the standards from being forced or bent toward each other when the nut 18 is tightened up. The transverse bar 15 constitutes the support for the engine block and for various other parts of the apparatus which may be attached thereto, and to this end the transverse bar 15 is formed with a plurality of perforations 21 spaced at any desired distance from each other.

For the purpose of holding the supporting bar 15 in any desired position, I form the supporting bar with an opening 22 and attach to one of the standards a pin 23 which is adapted to extend through the opening 22 and through one of a series of perforations 24 in the standard, this pin being connected to the standard by means of a spring 25. The standard has not only one opening 24 but a plurality of these openings so that the supporting bar 15 may be shifted into a plurality of positions. Thus it may be turned so that its upper face lies entirely in a horizontal plane or it may be shifted so that its outer face lies entirely in a vertical plane or to one or more intermediate positions, and under these circumstances the pin 23 will hold the supporting bar set or locked in this adjusted position.

The engine block A is adapted to be connected to the supporting bar 15 by the usual manifold studs α which are inserted through the apertures 21 in the supporting bar 15. Over these studs α and against the exterior

face of the bar are placed the sleeves 26, and engaging the outer ends of the studs *a* are the nuts 27 which bear against the ends of these sleeves. Thus the motor or cylinder bank will be held firmly supported upon the supporting bar 15 and the bar may be shifted to any desired position to thus hold the motor in proper position for working on.

In order to prevent the dropping out of the valves when the motor is shifted as described, I pivotally mount upon the ends of the supporting bar 15 the cross bar 28. This bar is supported by goosenecks 29 at its opposite ends, these goosenecks being formed integral with the bar 28 and extending and then downward in an approximate semi-circle from the bar 28 and being pivoted to the inwardly turned ends of the bar 13 by means of the rivets 30. This cross bar 28 has a plurality of apertures in it, and operating through these apertures are the headed pins 31. These pins at their inner ends are provided with transverse apertures for the passage of cotter pins 32, and surrounding each pin and bearing at one end against the head thereof and at its opposite end against the cross bar is a coiled spring 33 which acts to force the headed pins outward until stopped by the cotter pins 32. Thus these headed pins are normally projected and the springs resiliently resist the inward movement of the pins. These pins are disposed in alignment with the valve stems and bear against the valve. Riveted or otherwise attached to the cross bar 28 is a U-shaped clip 34, and having screw-threaded engagement through this clip is a cap screw 35. This cap screw is adapted to screw into the middle hole *b* in the engine block A where the cylinder head cap goes.

It will be seen that this cross bar 28 constitutes a valve holding device which may be turned upon its pivots 30 to bring the pins 31 into engagement with the valves and that when this device is brought down on the valves the screw 35 passes into and engages the opening *b*, as heretofore described. The downwardly turned ends of the U-shaped clip 34 bear against the face of the engine block and hold the cross bar 28 in such position that the pins 31 will bear properly against the valves and thus keep the valves from falling out when the motor block is swung to different positions. When these pins are engaged with the valves, the engine can be cranked and the stems of the valves will not be buckled, as the springs 30 will compress to permit the movement of the valves.

In order to provide means whereby the transmission, fly wheel, and magneto assembly can be supported on the lower portion of the stand, I provide the hook-like members 54 which at their upper ends are formed with eyes through which the bolt 14 passes

and which at their lower ends are angularly bent, as at 55, so that, as illustrated in Figure 1, the transmission mechanism, fly wheel and the magneto assembly may be supported by these hook-shaped members, thus adding weight to the bench or stand when heavy wrench pressure is used for tightening bearings. This motor stand will not twist or slide on a cement floor, as it is provided with small nubs at its four corners which rest upon the floor. At the same time the motor stand is sufficiently light so that it may be readily shifted to any desired part of the assembly room or garage. It will be seen that all of the parts can be readily manufactured and pressed cold and that they may be readily assembled. This stand, while it is particularly intended for use with Ford and Fordson motors, may be made to hold any engine block that has a manifold held by studs or bolts.

I claim:—

1. A motor stand comprising a bar having a face adapted to flatly abut the side wall of the block of an internal combustion engine and to be secured in position thereagainst and a pivotal support for the bar such that said block engaging face of the bar is tangential to the arc of swing of the bar.

2. A motor stand for motors having in a side wall thereof openings for the reception of securing elements for attaching to the motor a manifold thereof, said motor stand comprising spaced uprights and a cross bar pivoted to said uprights and swingable from side to side of the uprights about the pivots thereof and securable in adjusted positions, said cross bar having a motor engaging face arranged in a plane at right angles to a radius of the pivot of the cross bar and having openings therein for the passage of securing elements which engage in said openings of the motor wall, said securing elements constituting the sole connection between the motor and the motor stand.

3. A motor stand for motors having in a side wall thereof openings for the reception of securing elements for attaching to the motor a manifold thereof, said motor stand comprising spaced uprights and a U-shaped cross bar having the arms thereof pivoted to said uprights and swingable from side to side of the uprights about the pivots thereof and securable in adjusted positions, the bight portion of said cross bar forming a motor engaging support having its motor engaging face arranged in a plane at right angles to a radius of the pivot of the cross bar, said bight portion having openings therein for the passage of securing elements which engage in said openings of the motor wall, said securing elements constituting the sole connection between the motor and the motor stand.

4. A motor stand of the character described including supporting standards held in spaced relation to each other, a cross bar having angularly bent ends pivoted to said standards whereby the cross bar may be rotated into a plurality of angular positions, means for locking the cross bar in any one of its angular positions, and means carried by said cross bar and adjustable thereon for yieldingly engaging the valves of the engine block.
5. A motor stand of the character described including supporting standards held in spaced relation to each other, a cross bar having angularly bent ends pivoted to said standards whereby the cross bar may be rotated into a plurality of angular positions, means for locking the cross bar in any one of its angular positions, means carried by said cross bar and adjustable thereon for yieldingly engaging the valves of the engine block, comprising a transverse rod extending parallel to the cross bar and having U-shaped arms on the extremities of the rod, the ends of said arms being pivoted to the angularly bent ends of the cross bar, a plurality of resiliently projected studs carried by said rod, and means for holding the rod in its adjusted positions with the studs against the valves of the engine.
6. A motor stand of the character described including supporting standards held in spaced relation to each other, a cross bar having angularly bent ends pivoted to said standards whereby the cross bar may be rotated into a plurality of angular positions, means for locking the cross bar in any one of its angular positions, means carried by said cross bar and adjustable thereon for yieldingly engaging the valves of the engine block comprising a transverse rod extending parallel to the cross bar and having U-shaped arms on the extremities of the rod, the ends of said arms being pivoted to the angularly bent ends of the cross bar, a plurality of resiliently projected studs carried by said rod, a member mounted upon the rod at its middle, and a screw passing through the member and adapted to engage one of the cap screw holes of the engine block.
7. A motor stand of the character described including supporting standards held in spaced relation to each other, a cross bar having angularly bent ends pivoted to said standards whereby the cross bar may be rotated into a plurality of angular positions, means for locking the cross bar in any one of its angular positions, means carried by said cross bar and adjustable thereon for yieldingly engaging the valves of the engine block comprising a transverse rod extending parallel to the cross bar and having U-shaped arms on the extremities of the rod, the ends of said arms being pivoted to the angularly bent ends of the cross bar, a plu-
- 70 rality of resiliently projected engine valve engaging studs carried by said rod, a U-shaped member mounted upon the rod, and a cap screw passing through the U-shaped member and adapted to be inserted in and engaged with one of the cap screw openings of the engine block.
8. A motor stand of the character described comprising a support, a transversely extending supporting bar oscillatably mounted upon said support and having means for engaging an engine block therewith, means mounted upon said support for holding the valves of the engine from dropping out and including a rod, and spring projected pins 75 mounted upon the rod.
9. A motor stand of the character described comprising a support, a transversely extending supporting bar oscillatably mounted upon said support and having means for 80 engaging an engine block therewith, means mounted upon said support for holding the valves of the engine from dropping out and including a rod, spring projected pins 85 mounted upon the rod, and means mounted upon the rod for holding the rod in spaced relation to the face of the engine block.
10. A motor stand of the character described comprising parallel supporting standards, a block disposed between said standards, bolts connecting the standards and holding them against the ends of the block, a supporting cross bar having inwardly turned ends, a bolt passing through the inwardly bent ends and through the upper 90 ends of the standards and having a nut on one end, and a sleeve surrounding said bolt and disposed between the standards, said cross bar having means whereby an engine block may be clamped thereto.
- 95
11. A motor stand of the character described comprising parallel supporting standards, a block disposed between said standards, bolts connecting the standards and holding them against the ends of the block, a supporting cross bar having inwardly turned ends, a bolt passing through the inwardly turned ends and through the upper 100 ends of the standards and having a nut on one end, and a sleeve surrounding said bolt and disposed between the standards, said cross bar having means whereby an engine block may be clamped thereto.
- 105
12. In a motor stand support of the character described, a support, a swinging member oscillatably mounted upon the support and adjustable into a plurality of angular 110 positions, the swinging member having means whereby it may be engaged with an engine block, and means adjustably mounted upon the swinging member for resiliently bearing against the valves of the engine 115
- 120
- 125

4
block and holding said valves against their seats, said means including means for positively engaging the engine block.

13. A motor stand having spaced upright members and a transversely extending narrow bar flat upon one face and thus adapted to flatly abut the side wall of the block of an internal combustion engine adjacent the head end thereof, and to be secured in a position thereto, the bar having a plurality of apertures along its length adapted for the reception of stud bolts extending

from the engine block and being angularly bent at its extremities to lie flat against the upwardly extending members of the stand, 15 said angularly bent ends being pivotally engaged with said upwardly extending members, and means for locking the bar in any one of a plurality of angularly adjusted positions relative to said upwardly extending members. 20

In testimony whereof I hereunto affix my signature.

GEORGE M. PETERSON.
